UNITED STATES PATENT OFFICE.

GUSTAF BERGMAN, OF MARLBORO, MASSACHUSETTS, ASSIGNOR TO UNITED SHOE MACHINERY COMPANY, OF PATERSON, NEW JERSEY, A CORPORATION OF NEW JERSEY.

LASTING APPARATUS.

1,161,918.

Specification of Letters Patent. Patented Nov. 30, 1915.

Application filed January 6, 1912. Serial No. 669,773.

To all whom it may concern:

Be it known that I, GUSTAF BERGMAN, a citizen of the United States, residing at Marlboro, in the county of Middlesex and State of Massachusetts, have invented certain Improvements in Lasting Apparatus, of which the following description, in connection with the accompanying drawings, is a specification, like reference characters on the drawings indicating like parts in the several figures.

This invention relates to apparatus for lasting the toes of boots and shoes, the object of the invention being to provide a cheap, simple, compact and easily operated mechanism with which the uppers may be quickly and smoothly lasted, the illustrative embodiment of the invention herein shown being adapted for light work in lasting which a large output is desirable.

The several features of the invention will be disclosed in the following description of the illustrative apparatus, taken in connection with the accompanying drawings, and will be particularly pointed out in the claims.

Referring to the drawings:—Figure 1 is a front elevation of my improved lasting apparatus showing a shoe in position to be lasted and a portion of a bench in section. Fig. 2 is an enlarged plan view, partly broken away, of the lasting devices, with a portion of a shoe illustrated in connection therewith before the toe is lasted. Fig. 3 is a plan view, similar to Fig. 2, illustrating the position of the respective parts of the apparatus and a portion of a shoe with the toe lasted. Fig. 4 is a front elevation of the lasting devices, the same being partly broken away to save space in the drawings. Fig. 5 is a detail end elevation of the lasting devices with a last in section in connection therewith, illustrating the manner in which the toe portion of the upper is wiped over the last by the wipers. Fig. 6 is a detail plan of the toe wipers. Fig. 7 is a detail plan of the toe clamp. Fig. 8 is a longitudinal section of a last, with an upper in position to be lasted. Fig. 9 is an illustrative section, similar to Fig. 8, showing a portion of the lasting devices holding the upper in the position which is assumed as the lasting operation of the toe begins, this view being taken on line 9—9, Fig. 2. Fig. 10 is an illustrative section, similar to Fig. 9, show-

ing the position of the upper and of the lasting devices when the toe has been lasted, this view being taken on line 10—10, Fig. 3.

Referring to Fig. 1, 12 is a portion of a bench, 13 is a shoe upper and 14 a last 60 closed in said upper, said upper and the last in inverted position being supported upon a heel post 15 and a toe rest 16. A bell-crank lever 17 is pivoted at 18 to a bracket 19 fast to said bench, the horizontal arm of 65 said bell-crank lever being connected by a link 20 to a treadle 21 pivoted at 22 to a bracket 23 fast to the floor, said treadle being held upwardly by a spring 24 connected at one end to said treadle, and at the upper 70 end to the bench 12. A collar 25, fast to the link 20, limits the upward motion of the treadle 21 and the backward rocking movement of the vertical arm of the bell-crank lever 17. 75

A pair of crossed levers resembling pincers 26 is pivoted at 27 to the upper end of the vertical arm of the bell-crank lever 17 and to the lower jaw 28 of said pincers is pivoted at 31 a pair of toe wipers 29, 30, 80 said toe wipers being shown as round rods bent into approximately horseshoe shape and adapted to swing in a horizontal plane, or a plane substantially parallel to the sole of the shoe. The lower arms 33 and 34 of 85 a second pair of crossed levers or pincers 32 are pivoted at 35 and 36, respectively, to the toe wipers 29 and 30, and these arms are extended downwardly below said toe wipers and are provided with lateral projections 37 and 38, which extend, respectively, through holes 39 and 40 formed in the guide arms 41 and 42, said guide arms forming, in effect, a single U-shaped piece fastened by a screw-stud 43 to the under 90 side of the jaw 28, said screw-stud forming also a stop and being provided on its front face with a piece of leather or other soft material 44, Fig. 4, to prevent injury to the shoe when said stop is brought into contact with the toe portion thereof. 100

A toe clamp plate 45 is fastened to the upper jaw 46 of the pincers 26, said clamp plate being preferably of U-shape. The approach of the toe clamp plate 45 to the toe 105 wipers 29 and 30 is regulated by means of an adjusting screw 47 having threaded engagement with said upper jaw 46 and abutting against the lower jaw 28 when the pincers are closed by moving the handles 48 110

and 49 thereof toward each other in the usual manner. The second pair of pincers 32 have handles 50, 51 and are pivoted to each other by a pivotal bolt 52.

5 The operation of my improved lasting apparatus is as follows: Assuming the last, with its upper, to be clamped upon the toe rest 16 and heel post 15, as illustrated in Fig. 1, the upper then being in some such 10 relation to the last as shown for illustrative purposes in Fig. 8, the operator depresses the handle 49 to raise the toe clamp plate 45 away from the toe wipers 29 and 30. At this time the free ends of the toe 15 wipers 29 and 30 are held apart by the action of the handles 50 and 51 of the second pair of pincers 32. The operator now 20 folds the upper 13 of the shoe over the toe wipers 29 and 30 and the toe clamping plate 45 is brought downwardly by moving the handles of the pincers 26 together until the leather of the upper is clamped between the under side of the toe clamp plate 45 and the upper side of the wipers 29 and 30, Fig. 9, 25 and is pulled upwardly about the toe of the last. The operator now presses upon the treadle 21, rocking the bell-crank lever 17 upon its pivot 18 and moving the two pairs of pincers with the toe wipers and toe clamping plate forwardly or to the right (Fig. 1), 30 said parts being carried automatically downward about the pivot 18 as they are moved forwardly. This draws the upper over the toe of the shoe, as illustrated in 35 Fig. 10, and while this is occurring the operator moves the toe wipers toward each other and applies downward pressure upon the end portions of the wipers by manipulating the handles of the second pair of pincers 32, swinging the free ends of the toe 40 wipers inwardly toward each other and wiping the sides of the toe portion of the upper firmly over the inner sole of the shoe, as illustrated in Fig. 5. By pressing laterally 45 the second pair of pincers, as distinguished from merely closing them, the operator can close one wiper farther than the other one as may be required for the shape of the shoe. The sole may be coated with adhesive to 50 secure the upper or the operator may now tack the toe portion of the upper to the inner sole, or fasten it thereto in any desirable manner. He then releases the treadle 21 and opens apart the handles of the pincers 26 and 32, 55 the parts resuming the relative positions illustrated in Fig. 1. He next removes the shoe and the apparatus is in condition to operate upon another shoe for the purpose of drawing the toe of the upper over the last 60 as hereinbefore described.

It will be understood that the handles 48 and 49 of the pincers 26 are joined together by a pivot 53, the jaw 28 being an extension of the handle 48 and the jaw 46 being an 65 extension of the handle 49.

While I have described my invention as embodied in apparatus for lasting the toes of boots and shoes, it is evident that some features of the invention are also useful in apparatus for lasting the heel portion of the 70 uppers of boots and shoes.

Having thus explained my invention and described one embodiment thereof, I claim and desire to secure by Letters Patent of the United States:—

75 1. An end lasting apparatus having, in combination, means for supporting a last in inverted position, a lever fulcrumed in front of the last so supported and carrying toe embracing jaws, and means for actuating the jaws to cause them to embrace the toe, said lever being arranged for manipulation to operate the toe embracing jaws to wipe the upper up the sides of the last into lasted relation to the edge of the last bottom and said jaw actuating means being arranged for manual control during the upward wiping movement imparted to the jaws by the lever.

80 2. An end lasting apparatus having, in combination, means for supporting a last in inverted position, a lever fulcrumed in front of the last so supported, toe embracing jaws carried on the end of the lever that is adjacent to the toe, a clamp coöperating with said jaws to seize the toe portion of the upper, and manually controlled means for operating the clamp to control the force with 85 which the upper is held while the toe is being lasted.

90 3. An end lasting apparatus having, in combination, means for supporting a last in inverted position, a lever mounted in front of the last so supported and adjacent to the plane of the last bottom, toe embracing jaws mounted on the lever, and a 95 clamp coöperating with the jaws to seize the upper about the shoe toe, and manually controlled operating means for said lever and for the toe embracing jaws to effect the lasting operation.

100 4. An end lasting apparatus having, in combination, means for supporting a last in inverted position, a lever fulcrumed in front of the last so supported and adjacent to the plane of the last bottom, toe embracing jaws mounted on the lever, a clamp coöperating with the jaws to seize the upper about the shoe toe, said lever being arranged for operation to pull the upper up the sides of the last, and separate manually 105 controlled means for actuating the jaws to lay the upper over the shoe bottom.

110 5. An end lasting apparatus having, in combination, means for supporting a last in inverted position, a lever fulcrumed in front of the last so supported and adjacent thereto, toe embracing jaws mounted on the lever, means for actuating said jaws lengthwise of the shoe against the end of the shoe, and means for actuating the jaws trans- 115

versely of the shoe to embrace the toe, said lever being adapted for actuation to cause the jaws to wipe the upper up the sides of the shoe, the jaw operating means being arranged for manual control during the movements effected by said lever.

6. An end lasting apparatus having, in combination, means for supporting a last in inverted position, a lever fulcrumed in front of the last so supported and having toe embracing jaws mounted on the lever, means for actuating the lever to advance the jaws, and means for closing the jaws, said lever being adapted for actuation manually to lift and to depress the jaws.

7. An end lasting apparatus having, in combination, means for supporting a last in inverted position, a lever fulcrumed in front of the last so supported and having toe embracing jaws mounted on the lever, a co-operating clamp connected to the lever, said apparatus including means for actuating the clamp and jaws to seize and pull the upper, and means for effecting a bodily forward movement of the lever and the jaws, said levers having handle portions adapting them for manual operation to overlay the upper on the shoe bottom.

8. An end lasting apparatus having, in combination, means for supporting a last in inverted position, a lever fulcrumed in front of the last so supported and adapted to rock up and down, toe embracing jaws mounted on the lever, a second lever pivoted upon the first lever and a clamp carried thereby to grip the upper when it is outspread over the jaws, said levers having handle portions adapting them for manual operation.

9. An end lasting apparatus having, in combination, the crossed levers having operating handles, toe embracing jaws carried by one lever and a co-operating clamp actuated by the other lever to grip the upper when it is outspread over the jaws.

10. An end lasting apparatus having, in combination, the crossed levers having operating handles, toe embracing jaws carried by one lever, a co-operating clamp actuated by the other lever to grip the upper when it is outspread over the jaws, and a support on which the levers are fulcrumed for movement together to stretch the gripped upper up the sides of the toe.

11. An end lasting apparatus having, in combination, the crossed levers having operating handles, toe embracing jaws carried by one lever, a co-operating clamp actuated by the other lever to grip the upper when it is outspread over the jaws, and means for advancing and closing the jaws to overlay the upper upon the shoe bottom.

12. An end lasting apparatus having, in combination, means for supporting a last, a lever fulcrumed in front of the last and

having a handle by which it can be moved up and down and also laterally, toe embracing wiper jaws carried on said lever, means to advance the jaws, and means to close the jaws, said lever mounting permitting movement of the lever to shift the jaws together in the same direction transversely of the shoe.

13. An end lasting apparatus having, in combination, means for supporting a last, end embracing wiper jaws, operating means actuated by a foot treadle for advancing the jaws over the shoe bottom and hand operated means for closing the jaws.

14. An end lasting apparatus having, in combination, means for supporting a last, end embracing wiper jaws, means arranged to be operated by one hand of the workman to raise the jaws, means arranged to be operated by a foot of the workman for advancing the jaws, and means arranged to be operated by the second hand of the workman for closing the jaws.

15. An end lasting apparatus having, in combination, means for supporting a last, end embracing wiper jaws, toe embracing wiper jaws, a clamp co-operating with said jaws to seize the upper about the toe, levers arranged to be actuated by one hand of the workman operating the jaws and the clamp, and a foot treadle for advancing the wipers to overlay the upper.

16. An end lasting apparatus having, in combination, toe embracing wiper jaws, means for advancing them over the shoe bottom and means for closing them, said closing means engaging the jaws near their rear ends and being arranged for applying downward pressure to the end portions of the jaws while they are being closed.

17. An end lasting apparatus having, in combination, toe embracing wiper jaws comprising round rods bent to horseshoe shape, and means for actuating the wiper jaws to rub up the sides and inwardly over the bottom of the toe.

18. An end lasting apparatus having, in combination, toe embracing wiper jaws, a co-operating clamp to grip the upper upon the outer end portions of the jaws along the sides of the toe at or adjacent to the tip seam location, means for rocking the jaws and clamp together about a horizontal axis extending transversely of the shoe and a substantial distance in front of the toe to pull the upper up the side faces of the toe and to a greater extent near the free ends of the wipers than at the middle of the toe, and means for operating the wiper jaws to overlay the upper upon the shoe bottom.

19. An end lasting apparatus having, in combination, toe embracing wiper jaws, a co-operating clamp between which and the jaws the upper may be gripped, said clamp including means for holding the upper upon

- the jaws at the sides of the toe, and actuating means for moving said jaws and clamp to pull the upper upwardly and then to overlay it, said parts being arranged for greater 5 pulling movement at the said sides than at the end of the toe.
20. An end lasting apparatus having, in combination, toe embracing wiper jaws, and means for advancing the wiper jaws over 10 the shoe bottom to overlay the upper, said means being constructed and arranged to move the jaws downward as an incident to their advance movement.
21. In an apparatus for lasting the uppers 15 of boots and shoes, a pair of pincers, a pair of toe wipers pivoted to one jaw of said pincers, and a second pair of pincers the jaws of which are pivoted respectively to the free ends of said wipers.
- 20 22. In an apparatus for lasting the uppers of boots and shoes, a lever, a pair of pincers pivotally supported upon said lever, a pair of toe wipers pivoted to one jaw of said pincers, and a second pair of pincers, the 25 jaws of which are pivoted respectively to the free ends of said wipers.
23. In an apparatus for lasting the uppers of boots and shoes, a pair of pincers, a pair of toe wipers pivoted to one jaw of said 30 pincers, two guide arms fast to said jaw and

extending forwardly therefrom outside said wipers, and a second pair of pincers, the jaws of which are pivoted respectively to the free ends of said wipers, and lateral projections upon the free ends of said last 35 named jaws extending through holes provided in said guide arms.

24. In an apparatus for lasting the uppers of boots and shoes, a pair of pincers, a pair of toe wipers pivoted to one jaw of said 40 pincers, a toe clamp plate fast to the other jaw of said pincers, and a second pair of pincers the jaws of which are pivoted respectively to the free ends of said wipers.

25. In an apparatus for lasting the uppers 45 of boots and shoes, a lever, a pair of pincers pivotally supported upon said lever, a pair of toe wipers pivoted to one jaw of said pincers, a toe clamp plate fast to the other 50 jaw of said pincers, and a second pair of pincers the jaws of which are pivoted respectively to the free ends of said wipers.

In testimony whereof I have signed my name to this specification in the presence of two subscribing witnesses.

GUSTAF BERGMAN.
